UNITED STATES PATENT OFFICE.

ISAAC VAN HAGEN, OF CHICAGO, ILLINOIS.

MACHINE FOR FORMING CORNER-PIECES FOR STOVE-BOARDS.

SPECIFICATION forming part of Letters Patent No. 355,235, dated December 28, 1886.

Application filed March 17, 1886. Serial No. 195,599. (No model.)

To all whom it may concern:

Be it known that I, ISAAC VAN HAGEN, of Chicago, in the county of Cook and State of Illinois, have invented certain new and useful 5 Improvements in Machinery for Forming Corner-Pieces for Stove-Boards, of which the following is a specification, reference being had to the accompanying drawings, and to the letters of reference marked thereon.

10 The object of this invention is to bend, or bend and corrugate, the corner-pieces used with that class of stove-boards which are composed of a sheet or sheets of metal attached to a wooden base, and in which, necessarily, the 15 corners of the wooden base would be exposed without the presence of a corner-piece separate from the sheet or sheets forming the main cover of the board.

In the accompanying drawings, Figure 1 is 20 a vertical section of my improved machine in one of its positions. Fig. 2 is a similar view showing the machine in another position. Fig. 3 is a top view of the machine in the position shown in Fig. 1. Fig. 4 is a top view of the 25 machine in the position shown in Fig. 2. Figs. 5, 6, and 8 are details. Fig. 7 is a perspective view of a corner-piece made by the machine constituting my invention.

Similar letters of reference indicate similar 30 parts in the respective figures.

A is the frame or support of the machine, which is provided with standards *a b*. In these standards are supported shafts *c d*, which are 35 geared together by toothed wheels *e f*. The shaft *c* is supported in fixed bearings, while the bearing for the shaft *d* in the standard *a* is provided with a movable upper box, *g*, and with an adjusting-screw, *a'*, whereby the pressure 40 on the shaft *d* may be regulated at pleasure. The bearing for the other end of the shaft *d* is pivoted to a support, *b'*, which is attached to the top plate, *b''*, by means of the screw *b'''*. The end of the shaft *d* which projects beyond the support *b'* is provided with a ring, *d'*, to 45 which is attached a spiral spring, *d''*, which is connected at its other end to a hook, *d'''*, fastened to the frame *A*. The shafts *c d* are provided with corrugating rollers or wheels *c' d'*, which extend beyond the front standard, *a*. 50 The frame *A* is provided with supports *e''*, (see Fig. 3,) to which is hinged by pins *e'*

f' a strap or yoke, *B*, having a cross-bar, *D*. To the cross-bar *D* is riveted a bar, *E*, formed in the shape of an arch, in which is a hole through which passes the pin *g'*, which is loosely attached to the disk *G*, and enters the projection *g''* on the bar *D*. The arched bar *E* also forms a support for the disk *G*. To the upper part of the strap or yoke *B* is hinged at *g'''* a spring strap or latch, *C*: (Shown elevated 55 in dotted lines in Fig. 4, and closed or latched in full lines in the same figure.)

F is a second disk, which fits over and concentrically with the disk *G*. The disk *F* is provided at its center with a pin, *h'*, which 60 passes loosely through the bar *H*, and is held in position by means of a washer, *h''*, and pin *h'''*. The bar *H* is attached to the strap or latch *C* by means of the thumb-screws *h^t*, which are provided with adjusting-nuts *h^s*, by means 65 of which the distance between the bar *H* and the strap *C* can be regulated. The bar *H* is provided with small wheels *i i*—one near each end—to relieve the friction between the bar *H* and the disk *F* when the latter is revolved. 70

The disk *G* is provided with pins *j*, as shown in Fig. 6. These pins are for the purpose of holding the blanks *k* in position by means of the holes *k'*. The disk *F* is grooved at *k''* for the purpose of receiving the pins *j* and to allow 75 the faces of the disks *F* and *G* to be brought close together.

In operation, supposing the machine to be in the position shown in Fig. 1, the latch *C*, together with the bar *H* and the disk *F*, is 80 lifted up, as shown in dotted lines, Fig. 4. The movable box *g* is raised up from the shaft *d*, and the spring *d''* will then operate to raise the corrugated roller *d'* from the corrugated roller *c'*. Four segmental pieces, *k*, of tin or other metal, are placed upon the disk *G*, the pieces being held in position by means of the pins *j* and holes *k'*. They are then clamped between the disks *F* and *G* by means of the latch *C*, the hook *l* of which springs upon the under side 85 of the strap or yoke *B*. The edges of the pieces *k* will extend beyond the edges of the disks *F* and *G*, and pass between the corrugated rollers *c' d'* a distance equal to the part to be bent over and corrugated. The upper shaft, *d*, having been forced down by the screw *a'*, so as to 90 press the corrugated roller *d'* onto the metal, 95

- the yoke B is gradually allowed to fall to the position shown in Fig. 2. The crank J is turned as the yoke falls, and the edges of the segmental pieces k will be bent to a right angle 5 and at the same time corrugated. The number of revolutions having been given to the corrugating-rollers necessary to effect the corrugating and bending of the corner-pieces, the upper bearing of the shaft D is loosened, the hook l of the latch C is released by means of the handle I, and the latch C and the disk F 10 are again elevated, as shown in dotted lines, Fig. 4, when the segmental pieces k, now formed into corner-pieces, are removed.
- 15 While I prefer to operate upon four plates or corner-pieces at one time, it is obvious that a greater or lesser number may be coincidentally treated.
- 20 By the use of my invention great rapidity of operation and accuracy of finish are effected.
- Having described my invention, I claim—
1. In a machine for bending and corrugat-

ing, the combination of a frame, adjustable corrugating-rollers, a hinged yoke having a cross-bar, D, and spring-latch C, clamping-disks F G, bar H, and adjusting-screws h⁴, substantially as and for the purpose specified.

2. In a machine for bending and corrugating, the combination of a frame, adjustable corrugating-rollers, hinged yoke having a cross-bar, D, and spring-latch C, releasing-lever I, clamping-disks F and G, bar H, having the wheels i, and adjusting-screws h⁴, substantially as and for the purpose set forth.

3. The clamping-disks F and G, one disk 35 having pins j, and the other disk being provided with a groove, k", substantially as and for the purpose specified.

In testimony whereof I have hereunto set my hand and seal.

ISAAC VAN HAGEN. [L. S.]
